[57] CLAIM

I claim the ornamental design for a railroad tie with quick lock sockets, as shown and described.

DESCRIPTION

FIG. 1 is a front, top and side perspective view of the railroad tie with quick lock sockets showing my new design;

FIG. 2 is a front elevational view thereof, the rear being a mirror image of the front shown in FIG. 2;

FIG. 3 is an end elevational view thereof, the end opposite being a mirror image of the end shown in FIG. 3; FIG. 4 is a top plan view thereof; and, FIG. 5 is a bottom plan view thereof.

FIG. 1

FIG. 2

FIG. 3

FIG. 4

FIG. 5
